UNITED STATES PATENT OFFICE

EARL RAYMOND SNEDAKER, OF PHILADELPHIA, PENNSYLVANIA, ASSIGNOR TO CARLTON PRODUCTS, OF PHILADELPHIA, PENNSYLVANIA, A CORPORATION OF PENNSYLVANIA

DESIGN FOR A GAME BOARD, TARGET, OR SIMILAR ARTICLE

Application filed November 7, 1932. Serial No. 45,797. Term of patent 3½ years.

To all whom it may concern:

Be it known that I, EARL R. SNEDAKER, a citizen of the United States, residing at Philadelphia, in the county of Philadelphia and State of Pennsylvania, have invented a new, original, and ornamental Design for a Game Board, Target, or Similar Article, of which the following is a specification, reference being had to the accompanying drawing, forming part thereof.

The figure is a plan view of a game board, target, or similar article having a flat piece of material of no appreciable thickness applied thereto and showing my new design thereon.

I claim:

The ornamental design for a game board, target, or similar article as shown and described.

E. RAYMOND SNEDAKER.
